UNITED STATES PATENT OFFICE.

WILLIAM G. HAWLEY, OF ELMIRA, NEW YORK.

SPLINED GEARING.

Application filed March 25, 1924. Serial No. 701,706.

To all whom it may concern:

Be it known that I, WILLIAM G. HAWLEY, a citizen of the United States, and a resident of Elmira, county of Chemung, and State 5 of New York, have invented certain new and useful Improvements in Splined Gearing, of which the following is a specification.

This invention relates to that class of gearing in which a gear is suitably mounted 10 upon a shaft so that it may be readily moved along said shaft but forced to rotate therewith. Heretofore, this class of gearing has been constructed in various forms, each form having its own peculiar drawback. 15 Thus, in the use with a square shaft of a gear having a bore sufficiently free to permit it to slide axially thereon, it is slow, expensive and almost impossible to accurately 20 grind the square hole in the gear hub for the purpose of correcting the distortion therein after said hub has been hardened. In another form a round shaft and slideable gear are both provided with milled or broached 25 key-ways, a key being inserted in said key-ways for holding the gear against rotation on the shaft but permitting said gear to slide axially along said shaft. This construction is subject to several drawbacks.

The shaft is weakened by having key-ways 30 cut therein. When the shaft is hardened by a heat treatment, these key-ways are distorted and in consequence, when the keys are inserted, the hardened bearing surface on the shaft is warped. Added to this is the fact 35 that it is a very difficult if not impossible operation to properly grind the key-ways of small gears like those used for automobiles, for example.

It is desirable that the spline gear and the 40 spline shaft shall have a truly cylindrical bearing one upon the other and also that these bearing surfaces shall be hardened. But the process of hardening causes more or less distortion or warping of these cylindrical 45 bearing surfaces, so that some expedient must be employed for overcoming this difficulty with a view to producing a true cylindrical surface after hardening. Two methods have been employed for this purpose, namely, one in which the gear is made 50 to fit upon the outer diameter of the splines; and the other in which the gear takes its bearing upon the portions between the splines. In the former method according to 55 which the inner bore of the gear was made to bear directly upon the top surfaces of the

splines, when it came to the heat treatment of gears with small hubs, it was found to be practically impossible to accurately grind the innermost surfaces of the splineways. 60 By the latter method, it has been customary to manufacture shafts with integral splines by cutting the splines, hardening them by heat treatment, and subsequently grinding the shafts to exact dimensions on the bottom of the grooves and the sides of the splines. A spline shaft can thus be made accurate by grinding and a good running condition of the gears which slide thereon, secured. This is due mainly to the fact 65 that the cylindrical portions of the bore in the hub of a gear, can be accurately ground under commercial conditions. The shaft can then be made to fit the ground bore of the gear hub, by properly hardening and 70 grinding the cylindrical surface thereof. This grinding operation, however, involves the use of peculiarly shaped grinding 75 wheels and the provision of specially designed devices for maintaining said grinding wheel in proper shape and in suitable relation to the work while the operation is in progress.

One of the objects of this invention is to 80 provide an improved construction for spline shafts and gears in which true cylindrical bearing surfaces between shaft and gears may be secured in a simple and effective manner.

Another object is to provide a variable 85 speed transmission mechanism of improved construction and an improved combination and relation of parts therein whereby the transmission mechanism can be economically constructed and a high degree of precision obtained by the employment of usual 90 shop methods. Toward the attainment of this object and as an adaptation of the principles underlying the present invention, the embodiment shown on the drawings includes 100 a spline shaft provided with integrally formed splines which have been hardened and afterwards ground to a true cylindrical surface over the top surfaces thereof. Mounted on this shaft and having its inwardly presented splines meshing with the splines on said shaft, is a gear which is provided with axially spaced inserted bearings 105 which have been machined, hardened and ground, prior to being inserted into said gear. The hardened and ground inner cylindrical surfaces of these inserted bearings 110

have an exactly dimensioned hardened bearing surface on the top surfaces of the shaft splines. While the following specification more especially discloses my invention with respect to a shaft having integrally formed splines it will be obvious that the same general considerations apply to round shafts with inserted keys and squared shafts.

In the drawings exemplifying my invention—

Figure 1 is an axial section of a gear set, showing an adaptation of my invention, parts being broken away and parts being shown in elevation;

Figure 2 is an enlarged fragmentary portion of Figure 1 showing the spline shaft in elevation and certain hub portions of the gear in section;

Figure 3 is a section on the line 3—3, Figure 2, parts being broken away and parts shown in elevation, and

Figure 4 is a section on the line 4—4, Figure 2, parts being broken away and parts shown in elevation.

Referring more particularly to the drawings, a housing 1, is provided at one end with a bearing casing 2. The drive shaft 3 which receives its power from the engine (not shown) is journaled in axially spaced ball bearings 4 and 5. The inner belled end 6 of the shaft 3 accommodates the ball bearings 7 for one end 8 of a spline shaft 9. The other end 8' of said spline shaft is journaled in ball bearings 10 adjacent the other end of the housing 1. The belled end 6 of shaft 3 is provided exteriorly with a spur gear 11 permanently in mesh with a spur gear 12 keyed to the countershaft 13 by a key 14. The inner belled end of shaft 3 also carries an external spur gear 15 which is adapted to mesh with an internal spur gear 16 with which an axially movable gear 17 is provided. An exterior spur gear 18 with which the gear 17 is also provided, may be thrown into and out of mesh with a spur gear 19 by means of suitable gear shifting means (not shown) operating in a circular groove 20. Said gear 19 is keyed to the countershaft 13 by means of a key 21. Axially spaced from the gear 17 and internally meshing with the spline shaft, is a double gear block 22 provided with a circular groove 23 in which suitable gear shifting mechanism may operate. Said gear block comprises a larger spur gear 24 and a smaller spur gear 25, the former being adapted to be thrown into and out of mesh with a gear pinion 26 on the countershaft 13 and the latter being adapted to be thrown into and out of mesh with a spur gear 27 on the countershaft 13. By means of the above described gears, in connection with the variable driving connections thru the sliding spline gears, the usual selection of speeds may be made.

Referring now to Figures 2, 3 and 4, a specific description of the spline gear connections between the left-hand gear 22 and the spline shaft 9 will serve also for the corresponding connections between the right-hand gear 17 and said spline shaft. In order to avoid as far as possible unnecessary machine and grinding operations and to make such operations as simple as possible, the present invention contemplates the arrangement of suitable cylindrical bearing surfaces to permit relative axial movements between gear and spline shaft as well as a suitable construction of parts for enabling said bearing surfaces to be ground to a true cylindrical form after they have been hardened by a heat treatment. For this purpose, the top surfaces 33 of the splines 9, are turned, hardened and ground to a true cylindrical surface with respect to the axis of spline shaft 3. This is a simple grinding operation which may be conducted in the usual well known manner. In order to avoid the necessity for grinding the bottoms of the grooves in the bore of the gear, the hub of said gear is provided with axially spaced cylindrical recesses 28 which may be readily machined and finished. Within said recesses are inserted bearing rings 29, which have been turned, hardened and ground to true cylindrical surfaces before their installation in position to serve as axially spaced bearings for the hardened and ground top surfaces of the splines 9 on the spline shaft. The grinding operation on the hardened bearing rings 29 is a simple case of cylindrical grinding which may be accomplished without difficulty in a well known manner. Suitable means for releasably securing the bearing rings 29 in position within the hubs of gears 17 and 22, may be provided by springing wire rings 30 into suitable circular grooves 31 with which the cylindrical walls of recesses 28 are provided for this purpose. As shown in Figure 3, the ends of wire rings 30 are spaced apart and provided with inwardly turned ends 32 by means of which said rings may be contracted and withdrawn whenever it is desired to do so. The advantages of this construction are obvious from the above description and briefly related are those resulting from a combination and relation of elements which by reason of their simple form and freely accessible bearing surfaces, are adapted to be trued by a simple grinding operation after being hardened by a heat treatment for the purpose of securing a true bearing contact permitting an axial movement between a spline shaft and the gear in mesh therewith.

I claim:

1. The combination with a spline shaft, of an internal gear meshing therewith, said gear being provided with inserted hardened

and ground bearings in bearing contact with corresponding bearing surfaces on said spline shaft.

2. The combination with a shaft provided with splines, of a gear having inwardly presented splines meshing therewith, and bearings separately finished and inserted into said gear, said inserted bearings having their inner surfaces bearing on the top surfaces of said splines.

3. The combination with a shaft, of a gear movable axially on said shaft but non-rotatably connected thereto, and bearings for said gear, said bearings being separately finished and applied to said gear.

4. The combination with a spline shaft, of a gear meshing therewith and movable axially thereof, and separately finished bearings inserted into said gear and bearing on the top surfaces of said splines.

5. The combination with a spline shaft, of a gear non-rotatably mounted thereon but movable axially thereof, and separately finished axially spaced bearings inserted in the bore of said gear.

6. The combination with a spline gear, of a gear non-rotatably mounted thereon, said gear being provided with recesses adjacent opposite ends of the bore therein, and bearings inserted in said recesses, said bearings being provided with inwardly presented bearing surfaces bearing on the top surfaces of said splines.

7. The combination with a shaft provided with axially extending splines hardened and ground on the top surfaces of said splines, of an internal gear meshing with said splines and provided with axially spaced recesses in the bore thereof, and separately hardened and ground bearing rings inserted in said recesses and bearing on the tops of said splines.

8. The combination with a shaft provided with axially extending splines hardened and ground on the top surfaces of said splines, of an internal gear meshing with said splines and provided with axially spaced recesses in the bore thereof, separately hardened and ground bearing rings inserted in said recesses and bearing on the tops of said splines and means for releasably securing said bearing rings in said recesses.

9. The combination of a hardened steel shaft with integral splines having their outer peripheral bearing surfaces ground true with respect to the axis of said shaft,

a gear in mesh with said splines and having inter-tooth spaces of larger diameter than said bearing surfaces and with axially spaced cylindrical recesses coaxial with said shaft, and hardened steel rings seated within said recesses and having inwardly presented bearing surfaces ground true with respect to the bearing surfaces on said splines.

10. The combination of a shaft with outwardly presented hardened splines provided with peripherally ground bearing surfaces trued with respect to the axis of said shaft, and a gear having axially spaced unbroken bearing surfaces hardened and ground true with respect to the bearing surfaces of said splines on which they bear.

11. The combination with a gear having axially spaced internal bearings which are hardened and cylindrically ground true with respect to the axis of said gear, of a shaft with outwardly presented splines with hardened outer peripheries cylindrically ground with respect to the axis of said shaft and in slidable engagement with said bearings on the gear.

12. The combination of a hardened steel shaft with integral splines having their outer peripheral bearing surfaces ground true with respect to the axis of said shaft, a gear having axially spaced cylindrical recesses coaxial with said shaft, and hardened steel rings seated within said recesses and having inwardly presented bearing surfaces ground true with respect to bearing surfaces on said splines.

13. The combination of a shaft with outwardly presented splines provided with hardened and ground top surfaces and a gear having an inner bore larger than the diameter of the shaft between said splines and inwardly presented splines having a root diameter greater than the outer diameter of said splines on the shaft, and axially spaced bearing surfaces hardened and ground true with respect to the bearing surfaces of said splines on which they bear.

14. The combination with a gear having axially spaced internal bearings which are hardened and ground true with respect to the axis of said gear, of a shaft with outwardly presented bearing surfaces hardened and ground true with respect to said internal bearing on the gear, said gear being non-rotatably connected to said shaft.

WILLIAM G. HAWLEY.
